UNITED STATES PATENT OFFICE.

HOWARD E. HARBAUGH, OF KENOSHA, WISCONSIN.

SASH OR SHUTTER OPERATING AND FASTENING DEVICE.

1,113,334.

Specification of Letters Patent.

Patented Oct. 13, 1914.

Application filed May 25, 1914. Serial No. 840,704.

To all whom it may concern:

Be it known that I, HOWARD E. HARBAUGH, a citizen of the United States, residing at Kenosha, in the county of Kenosha and State of Wisconsin, have invented certain new and useful Improvements in Sash or Shutter Operating and Fastening Devices, of which the following is a specification.

10 This invention relates to operating and fastening devices designed primarily for use in connection with window sash or shutters of that type wherein the sash or shutter is hinged on a vertical axis to open 15 outwardly of the window opening.

The general object of the invention is to provide a simplified and improved device of this character, and one which shall be capable of operation by a combined lifting 20 and swinging movement of a single handle or like manually-operated actuating means.

Other objects and advantages of the invention will be apparent from the following description of the invention and its mode 25 of manipulation and use, taken in connection with the accompanying drawing forming a part of this specification, and in which,—

Figure 1 is a horizontal section through a 30 portion of a window frame and sash, showing my improvement applied thereto. Fig. 2 is a fragmentary elevation from the inner side of the window. Fig. 3 is a sectional detail on the line 3—3 of Fig. 1. Fig. 4 is a 35 sectional detail on the line 4—4 of Fig. 1. Fig. 5 is a fragmentary top plan view showing the pivoted fulcrum member and a portion of the operating lever rotatably mounted therein on an axis at right angles to the 40 pivot axis of the fulcrum member. Fig. 6 is a perspective elevation of the cover piece or cap of the fulcrum member.

Referring to the drawings, 10 designates the sill, and 11 one of the vertical side 45 frames of the window-jamb.

12 designates the window sash, pivotally mounted at the outer side of the jamb-frame member 11 on vertical hinges 13, after the fashion of casement windows, so as to swing 50 outwardly, as indicated by dotted lines in Fig. 1, and 14 designates the usual glazing carried by the sash 12.

15 designates a screen-sash slidably mounted on the inner side of the window-sash in 55 suitable ways or grooves 16, the use of such screen-sash being entirely optional so far as

the present invention is concerned, but being herein illustrated because commonly employed in connection with windows of the type illustrated.

Secured to the lower portion of the inner side of the window-sash frame 12 is a horizontal stop-bar which comprises an intermediate body portion 17 (Fig. 3) attached to the sash-bar by screws 18, a lower channel portion 19 in which are formed a plurality of uniformly-spaced holes 20, and an upper, overhanging, confining rib or ledge 21. Secured to the sill 10, by screws 22, is a round disk or plate 23, on which is 70 rotatably mounted, on a vertical pivot stud 24, a hollow or cup-shaped fulcrum-block 25; the pivot stud 24 being preferably headed so as to secure the fulcrumed block 25 on the base-plate 23, and the bottom member of the fulcrum block being apertured, as indicated in Fig. 5, to permit the passage therethrough of the fastening screws 22. Journaled in the fulcrum block 25 on a horizontal axis is an operating lever comprising, 75 on one side of said fulcrum block, a laterally bent arm 26, and, on the other side of the fulcrum member, a laterally bent handle 27, which latter, for convenience in assembling, is preferably united to the journal 80 shank of the arm 26 by a screw-threaded joint 28 (Fig. 4) keyed against turning movement by a pin 29. It will be observed, by reference to Fig. 1, that the arm 26 and the handle 27 of the operating lever extend 85 horizontally at an angle to the axis of rotation of the lever and on the same side of said axis of rotation with reference to a vertical plane determined by the horizontal axis of the lever and the vertical axis of 90 the fulcrum block. The stop-bar engaging end of the arm 26 is somewhat widened and flattened, and in the same is secured a double-ended, tapered stud 30, the depending end of which slidably engages the channel 95 19 of the stop-bar when said arm is raised sufficiently to disengage said stud from the holes 20. At such time, the rising movement of the arm 26 is limited by the engagement of its extreme outer end with the confining rib 21 of the stop-bar, so as to prevent disengagement of the arm from the stop-bar under such rising movement.

31 designates a cover piece or cap that fits within the hollow fulcrum-block 25, the 110 same being slotted, as shown at 32, to straddle the shank portion of the operating arm

26 that is journaled in the fulcrum-block; said cap being preferably employed to enhance the neat appearance of the device and prevent the accumulation of dirt within the 5 hollow fulcrum-block.

The operation of the device will be readily apparent from the foregoing description. Assuming that the sash is in the closed position indicated in full lines in Figs. 1 and 2, 10 to open the same the operator merely grasps the handle 27, raises it sufficiently to disengage the stud 30 from the extreme left-hand hole of the stop bar, and then swings the handle 27 to the left until the sash is opened 15 to the desired extent, and then allows the handle to drop, when the stud 30 is in register with one of the intermediate holes or the extreme right-hand hole of the stop-bar. By reason of its tapered form, the stud 30 engages 20 the hole 20 with a comparatively tight fit, thereby locking the sash in open position and holding it securely against rattling. When the sash is to be closed, this is effected by the simple reverse of these operations 25 in an obvious manner. By equipping the operating lever with the double-ended locking stud, the device is equally adapted for use with a sash that opens to the right or to the left; the operating lever when used 30 for either being, obviously, simply inverted relatively to its position when used for the other. Where the screen sash 15 is used, the lower, horizontal frame-member of said sash is mortised out, as shown at 33 in Fig. 2, to 35 fit snugly over the fulcrum-block.

Without limiting myself to the precise details of construction shown and described, I claim:

1. In a sash operating and locking mechanism, the combination of a stop-bar adapted 40 to be attached to a hinged sash, a pivoted arm-supporting member, and an operating arm rotatably mounted in said arm-supporting member on an axis approximately at 45 right angles to the pivot axis of the latter, said arm at one end slidably engaging said stop-bar, and said arm and stop-bar being provided with coöperating means for securing them against relative sliding movement 50 at intervals lengthwise of said stop-bar.

2. In a sash operating and locking mechanism, the combination of a stop-bar adapted to be attached to a hinged sash, an operating lever, and means for supporting said lever 55 with capacity for both vertical and horizontal swinging movement, said lever having an arm slidably engaging said stop-bar and a handle on the opposite side of said supporting means from said arm, and said arm and stop-bar being provided with coöperating means for securing them against relative sliding movement at intervals lengthwise of said stop-bar.

3. In a sash operating and locking mechanism, the combination of a stop-bar adapted

to be attached to a hinged sash, a pivoted fulcrum member, and an operating lever rotatably mounted in said fulcrum member on an axis at right angles to the pivot axis of the latter, said lever having an arm slidably engaging said stop-bar and a handle, and said arm and stop-bar being provided with coöperating means for securing them against relative sliding movement at intervals lengthwise of said stop-bar. 70

4. In a sash operating and locking mechanism, the combination of a stop-bar adapted to be attached to a hinged sash, a pivoted fulcrum member, and an operating lever rotatably mounted in said fulcrum member on an axis at right angles to the pivot axis of the latter, said lever having an arm extending at an angle to its axis of rotation and at its free end slidably engaging said stop-bar and a handle also extending at an angle to its axis of rotation and on the same side of the latter with reference to the common plane of said axes, said arm and stop-bar being provided with coöperating means for securing them against relative sliding movement at intervals lengthwise of said stop-bar. 75

5. In a sash operating and locking mechanism, the combination of a stop-bar adapted to be attached to a hinged sash and having a channel portion formed with a plurality of holes spaced lengthwise thereof and an overhanging confining member, an operating arm carrying at its free end a stud slidably engaging the channel portion of said stop-bar and adapted to engage any of said holes, and means for supporting said arm with capacity for both vertical and horizontal swinging movement, the free end of said arm when raised to disengage said stud from said holes engaging said confining member and being then slidable lengthwise of said stop-bar to a new position of adjustment. 95

6. In a sash operating and locking mechanism, the combination of a stop-bar adapted to be attached to a hinged sash, a bent operating lever having an arm provided at its free end with means for slidably and lockingly engaging said stop-bar in either of two relatively reversed positions of said lever, and a handle, and means for supporting said lever with capacity for both vertical and horizontal swinging movement. 100

7. In a sash operating and locking mechanism, the combination of a stop-bar adapted to be attached to a hinged sash and having a channel portion provided with a plurality of holes spaced lengthwise thereof, a bent operating lever having an arm engaging said stop-bar and a handle, means for supporting said lever between said arm and handle with capacity for both vertical and horizontal swinging movement, and locking studs on the upper and lower sides respectively of the 115 120 125 130

free end of said arm for engagement with the channel portion and holes of said stop-bar whereby said operating lever is adapted to serve either a right or a left opening 5 sash.

8. In a sash operating and locking mechanism, the combination of a stop-bar adapted to be attached to a hinged sash and having a plurality of spaced holes therein, an operating 10 arm mounted with capacity for both vertical

and horizontal swinging movement and slidably engaging said stop-bar, and a tapered pin in the stop-bar-engaging end of said arm adapted to have a tight fit in said holes whereby to prevent rattling.

HOWARD E. HARBAUGH.
